Primary Examiner — Marianne N Pandozzi*Assistant Examiner* — Jae Liang(74) *Attorney, Agent, or Firm* — Quickpatents, LLC;
Kevin Prince(57) **CLAIM**

I claim the ornamental design for a drinking bottle, as shown and described.

DESCRIPTION

FIG. 1 is a front elevational view of a drinking bottle, showing my new design, the rear elevational view, left-side elevational view, and right-side elevational view all being identical thereto;

FIG. 2 is a top plan view thereof;

FIG. 3 is a bottom plan view thereof; and,

FIG. 4 is a top perspective view thereof.
